COMBINED RADIO AND PENHOLDER

Richard R. Hirsch, 1830 N. Sheffield Ave., Chicago, Ill.

Filed Dec. 8, 1960, Ser. No. 63,152

Term of patent 7 years

(Cl. D56—4)

Figure 1 is a rear perspective view of a combined radio and penholder showing my new design; and

Figure 2 is a front perspective view thereof, illustrating the side not shown in Figure 1.

I claim:

The ornamental design for a combined radio and penholder, as shown.
